BOOK ROUNDING AND BACKING MACHINE

Leo Robbins and Jack Bendror, New York, N.Y., assignors to Printing Industries Equipment Inc., New York, N.Y.

Application September 15, 1955, Serial No. 534,551

9 Claims. (Cl. 11—5)

This invention relates to bookbinding apparatus, and more particularly to a machine for rounding and backing the pages or signatures of a book preparatory to the same being bound in covers.

As is known, it is the accepted practice in bookbinding to unite the pages of the book at the rear thereof with sewing, after which the pages are rounded or convexly curved at the back, and pages or signatures of said back are then displaced to form a joint at either edge. It is one of the objects of the present invention to provide an apparatus for rounding and backing a book as above described, and which apparatus will be capable of operating on books of various thicknesses and sizes; which will uniformly round and back the signatures, and accurately and effectively shape the joints of the backs of the pages or signatures in preparation for the binding operations to be subsequently performed.

It is an object of the invention to provide an apparatus of this character which will grip the pages; feed them to the required position for rounding and backing; hold the bundle or book or pages securely while the rounding and backing operations take place and then deliver the rounded and backed book from the apparatus.

It is another object of the invention to provide in an apparatus of this kind, means by which the backing roller will have its arc of movement automatically controlled according to books of various thicknesses, and without adjustment. This is desirable because the radius of the curve on the back of the book varies according to the thickness of the book, and it is important that means be provided for automatically adjusting the backing roller to books of different thickness.

With these and other objects to be hereinafter set forth in view, we have devised the arrangement of parts to be described and more particularly pointed out in the claims appended hereto.

In the accompanying drawings, wherein an illustrative embodiment of the invention is disclosed.

Fig. 1 is a side elevational view of a book rounding and backing apparatus as constructed according to the invention;

Fig. 2 is a perspective view of the book or batch of pages constituting the body of a book in readiness to be rounded and backed by the apparatus of this invention;

Fig. 3 diagrammatically shows parts of the apparatus receiving the book to be rounded and backed;

Fig. 4 shows similar parts of the apparatus which have rounded and backed pages;

Fig. 5 shows the rounded and backed bundle of pages;

Fig. 6 is a perspective view of the apparatus, with certain parts thereof being shown in section and other parts broken away to disclose construction;

Fig. 7 is a perspective view of the apparatus, as viewed from one end thereof;

Fig. 8 is a sectional view, taken substantially on the line 8—8 of Fig. 7, looking in the direction of the arrows;

2

Fig. 9 is a side elevational view of the mechanism shown in Fig. 8;

Fig. 10 is a somewhat diagrammatic view showing the operating elements of the machine, and

Fig. 11 is a view of a slightly modified construction, and Fig. 12 is a diagram indicating the controls for the hydraulic cylinders. Referring to the drawings, and particularly to Fig. 2 thereof, 1 indicates a batch or bundle of pages or signatures constituting the body of an unbound book. These pages are united at the rear and 2 by suitable sewing 3 of known character. The united pages, in the condition shown in Fig. 2, are in readiness to be shaped by the apparatus constituting the present invention. In said apparatus, the pages 1 are brought to rest manually or by suitable feed means, back down, upon a slidably-mounted supporting plate 4 (Fig. 3), until they are gripped between the rounding and feed rollers indicated respectively at 5 and 6, and moved downwardly thereby to be engaged and held between 10 the gripping jaws indicated respectively at 7 and 8. The jaw shown at 7 is a fixed jaw, while the jaw 8 is movable toward and away from the fixed jaw, by means to be presently described, to thereby co-operate with the fixed jaw in gripping the book and thereafter releasing it after 20 the backing operation has been performed. While the pages are thus supported by the jaws 7 and 8, a backing roller 9, which is initially located centrally of the back of the pages when the pages are brought down by rounding and feed rollers 5 and 6 and is in the position shown in full lines in Fig. 4, is arcuately moved across the backs of the pages in the book while applying pressure against them. This roller 9 is moved back and forth or reciprocated a few times across the back of the book and this results in the production of the backed rear 30 portion of the pages as indicated at 10 in Fig. 5. The rounded and backed book is shown in Fig. 5, and after the rounding and backing takes place as above described, the book is discharged from the machine and is then in readiness for the application of the covers.

In Fig. 6 is shown the linkage and levers by which the backing roller 9 is supported and is actuated. It will be understood that much of this mechanism is employed at both sides of the machine, that which is located at one side only, being shown in this view. At each end, the 40 shaft 11 of roller 9 is rotatively mounted at one end of a triangulated plate 12. One corner of the plate is pivoted at 13 to one end of a link shown at 14, which has its opposite end pivoted at 15 to one end of a second triangulated plate 16. A second end of the plate 16 is pivoted at 17 to one end of a lever 18 which has its opposite end pivotally mounted at 19 on a pin mounted in the side frame 20 of the machine. The third end or corner portion of the triangulated plate 16 is pivoted at 21 to one end of a lever 22 having its opposite end 45 pivoted at 23 in the side frame 20. The two levers 18 and 22, mounted as above described, provide a parallel movement for the triangulated plate 16.

Pivoted mounted on the pin 21 is one end of a link 24 which has its opposite end pivotally attached to a pin 25 projecting from one of the ends or corners of the 50 triangulated plate 12. At one end of the pin 25 is a bearing 26 operative in an elongated slot 27 formed in an arm 28 having one end secured at the end of a cross-piece 29 provided with a similar arm at its opposite end. The cross-piece 29 is provided with a clevis 30 in which the end of a piston rod 31 is pivoted. The piston rod 31 extends from a hydraulic cylinder 32 pivoted at 33 in the clevis 34 attached to a fixed cross member 35 or other fixed part of the machine frame. A second hydraulic cylinder is shown at 36, the same being pivotally connected at 37 to clevis 38 mounted on a cross bar 39 or

other fixed element in the machine frame. The piston rod 40 of hydraulic cylinder 36 is connected in the clevis 41 provided on the cross bar 29. The two hydraulic cylinders, indicated respectively at 32 and 36, are operative to cause an arcuate swinging movement of the backing roller 9 across the back of the book through the linkage thus far described in conjunction with other elements to be now enumerated and to position roller 9 centrally with respect to the book prior to the start of the swinging operation. In the diagram of Fig. 12, the cylinders 32 and 36 are combined and the operation thereof is controlled by the valve mechanism generally indicated at V4.

The end of the arm 28 is pivotally attached at 42 to one end of a link 43 which has its opposite end pivoted on the pin 44 mounted in a fixed part of the frame 20. Also mounted on the pin 42 is one end of a link 45 which has its opposite end pivotally attached at 46 to the movable jaw 8. Secured to the pin 25 and wound partially around it is one end of a chain 47 or similar flexible element, and said chain extends around pin 42 and also around a pin 48 extending from a fixed part of the machine. The second end of the chain, and which is partly shown in dotted lines in Fig. 6, is connected to one end of a turn-buckle 49, which has its opposite end terminating in a block 50 that is pivotally attached at 51 to an arm 52, having one end pivotally secured at 53 to a bracket 54 secured to and extending from the fixed jaw 7. The second end of the arm 52 is pivotally connected at 55 to one end of an arm 56 projecting radially from and secured eccentrically on shaft 57. A pinion 58 is secured on the shaft and said pinion is in mesh with a rack 59 on the piston rod of a hydraulic cylinder 60, having its lower end pivotally connected at 61 to a fixed cross member 62 of the machine frame. Through the arrangement described, the arm 56, having a crank movement will tend to create the proper tightening of chain 47 during movement of the backing roller 9 and slacken the chain upon completion of the backing operation.

The chain connected in the manner described, will automatically take care of the change of radius of movement of the backing roller in accordance with the various thicknesses of books.

The chain 47 accordingly tends to maintain the backing roller 9 at the proper position for engagement with books of various thicknesses and adjustment for the wear of the chain is had by means of a handwheel 63 rotatively mounted in one end of the machine frame. The handwheel is mounted on a threaded shaft 64, threadable into the block 65, which embraces the shaft 57. A sprocket 63a is secured on shaft 64 and this sprocket is connected by a chain, shown in dotted lines in Fig. 6 on another shaft adjacent to the opposite side of the machine, for securing uniform adjusting movement of shaft 57 throughout its length.

The movable jaw 8 is slidable toward and away from the fixed jaw 7 by hydraulic means including the cylinder shown at 66 controlled by the valve mechanism generally indicated at V1 in Fig. 12. Carried by, and slidably mounted on and in relation to the movable jaw 8, is the plate 4 which initially supports the book. The plate is moved back and forth at the required times by hydraulic means of cylinder 67 controlled by the valve mechanism generally indicated at V2.

The rollers 5 and 6 are supported in a pivoted frame, generally indicated at 70, and which includes the side members 71 and 72, (Fig. 8) connected by several cross members indicated at 73. The frame is pivotally mounted at one end in the lugs 74 and it has a limited upward and downward swing that is controlled by the stop members designated respectively at 76 and 77. Stop member 77 consists of an adjustable, threaded and headed stem 78 vertically adjustable through the bracket 76. On the lower end of the threaded stem 78 is provided a bevel gear 79 in mesh with a similar bevel gear 80 secured on

the adjustment shaft 81. A hand wheel 82 secured on the adjustment shaft 81 permits of manual rotation of said shaft so that stop member 77 can be thus raised or lowered accordingly to position the head on said stop at the location desired to limit the upward swing of frame 70. The frame 70 is provided with a yoke 84 which straddles the stem 78 of stop 77 and impinges against the head thereon when the frame is swung upwardly to the limit of such movement as determined by the head on stop 77. The frame 70 is raised and lowered by a hydraulic cylinder indicated at 85 controlled by the valve mechanism generally indicated at V2 and which has its piston rod connected to the yoke 84, as clearly seen in Fig. 6.

By limiting the movement of the frame 70, provision is made for various sizes of joints on the book. By setting the position of the head 77 at a point which will permit the frame 70 to rise to a predetermined height on the held book, the rollers will have a certain amount of travel and accordingly the book will be moved downwardly to a certain given position with respect to the jaws 7 and 8, thus allowing a certain amount of the book to be displaced by the backing roller to create a joint of a certain size. By positioning the head 77 so that the frame 70 will rise higher, the rollers 5 and 6 will grip the book at a higher point and will, upon rotation, advance the book to a lower position with respect to the jaws 7 and 8 thus causing a greater amount of the back portion of the book to project below the jaws and be displaced by the backing roller, and result in a large size of joint.

Roller 5 is rotatively mounted in bearings on one of the cross members 73 of the frame 70, one of said bearings being shown at 86, so that said roller is raised up and down in company with frame 70 and is rotated by means to be described. Roller 6 is also carried by the frame 70 and is rotative in bearings 87 and 87a (Fig. 8), supported by a movable cross bar 88. The cross bar has its ends mounted for slidable movement in slots 89 provided in the side members 71 and 72 of frame 70. Cross bar 88, carrying the roller 6 is moved toward and away from the book by the hydraulic cylinders indicated at 91 and 90 controlled by the valve mechanism generally indicated at V3.

The function of cylinders 91 and cylinders 90 may be explained as follows: Both cylinders 91 are single-acting. That is to say, they are capable of moving the rounding and feed roller 6 in the forward direction only, the feed roller 6 being retracted by hydraulic cylinders shown at 90. The rod ends of cylinders 90 and 91 are connected to the cross bar 88, which bar carries the roller 6, but the rear ends of cylinders 90 and 91 are mounted on the jaw 8 and are stationary while roller 6 is moving forwardly. When the movable jaw 8 moves forwardly, it carries with it the rear ends of the cylinders 90 and 91. Upon completion of the cycle, the roller 6 will retract by means of the cylinders 90, which are double acting, and will retract only as far as the movable jaw 8 will permit. The setting of the extent of retraction to be done by jaw 8 is accomplished by electrical and hydraulic means and is controlled by means of the switch 63 (Fig. 7). Thus, though the movement of roller 6 is independent of the movement of the jaw 8, it is possible to synchronize their relative positions.

In the bearing housing 87 for the roller 6 is a gear 109 (Fig. 8) on the end of the roller shaft 6a, and said gear 109 meshes with a worm 92 on one end of a shaft 93 provided at its opposite end with a pinion 94 in mesh with a rack 95 which is moved transversely of the machine by means of a hydraulic cylinder 96 controlled by the valve mechanism V2 and having its piston rod 97 connected to one end of the rack 95 as clearly shown in Fig. 7. Similarly, the bearing housing 86 for roller 5 contains a gear similar to gear 109, on the end of the shaft 5a of roller 5, which gear is in mesh with a worm gear 98 on shaft 99. At its opposite end, shaft 99 is provided

with a pinion 100 in mesh with the rack 95. Shafts 93 and 99 are provided with flexible couplings 101 (Fig. 7) if found desirable. It will be apparent that through the mechanism disclosed, the operation of the hydraulic cylinder 96 will be effective to move the rack 95 and cause rotation of the two shafts 93 and 99 thus rotating the rollers 5 and 6 in opposite directions and in a manner to cause the rollers to round the book and move it down to the required extent for engagement by the backing roller 9 when the roller is moved across the back of the book.

In Fig. 9 is shown means for providing for the adjustment of the relative size of the joints of the books according to the thickness of various books. It will therein be noted that at each side of the frame 70 is provided a cam finger 125 having an inclined upper edge 126 and moving between a pin or roller 127 extending laterally from the sides of the frame 70 and the pin or roller 127a extending from the fixed frame. The fingers 125 are pivotally supported by the ends of the bar 88 and control the extent of descent of the book between the jaws 7 and 8 to the point of backing. This is determined by the thickness of the cam 125 at the point of contact with the rollers 127 and 127a according to the extent to which the roller 6 is moved toward roller 5 and this is governed by the thickness of the book to be backed.

From the foregoing the operation of the described apparatus will be readily understood.

A book to be rounded and backed is inserted, manually or by feed mechanism, between the rollers 5 and 6 with its back brought to rest upon the supporting plate 4 substantially as shown in Fig. 3. The machine is set in operation by depression upon the control pedal shown at 120 in Fig. 1, whereupon roller 6 will be moved toward roller 5 to grip the book between them, and the plate 4 is retracted and brought out from under the back of the book now supported between the two rollers 5 and 6. As the rollers 5 and 6 are now rotated by the mechanism previously described, they will round the book and at the same time move it downwardly between them and between the jaws 7 and 8, with jaw 8 being moved toward jaw 7 to cause the book to be now engaged and held between the two jaws 7 and 8 as shown in Fig. 4, and with a sufficient portion of the rear part of the book projecting below the jaws to enable such projecting portion to be backed by the roller 9. At the time that the book is brought down to its backing position, the backing roller 9 is in its central or midway position, as shown in full lines in Fig. 4, and when the book has its rear end brought down into contact with the roller 9, the roller is then brought back and forth several times through an arc across the back of the book, causing the same to assume the desired rounded and backed condition substantially as shown in Fig. 5. The jaws 7 and 8 now separate, releasing the book, which thereupon falls down through a guide chute consisting of a curved plate 111 located below the jaws and resiliently mounted by means of the spring 112 and pivoted fingers 113 (Fig. 10).

The plate 111 cooperates with a fixed guide plate 110 to guide the book down to a position where it is received upon co-operating conveyor belts 114 and 115 which travel transversely of the machine and carry the rounded and backed book out of one side of the machine. The conveyor belts travel over rollers driven by a motor 118 and the bevel gearing 116 and 117.

In Fig. 11 is shown a modified construction, wherein the means for moving the backing roller 9 is simplified. In this embodiment, the triangular plate 16 has one of its ends pivoted at 130 to a link 131 which has its opposite end pivoted at 132 to one corner of the plate 12. The opposite corner of plate 12 is pivotally connected at 133 to one end of a link 134 which has its opposite end connected to the pivot 21. Connected between the pivots 132 and 133 to the plate 12, at the point 135, is one end of a short link 136 which has its opposite end pivoted at 137 to one end of a link 138 which is pivoted at 139

to a fixed part of the machine. Also secured on pivot 139 is arm 140 connected to the piston rod 141 of a hydraulic cylinder 142. With this arrangement a single hydraulic double-acting cylinder, namely, that shown at 142, is used to cause the backing roller to center and be moved through its desired arc by oscillations of the triangular plate 16 during the backing operation, and the mechanism is in other respects somewhat simplified.

Having described an embodiment of the invention, it is obvious that the same is not to be restricted thereto, but is broad enough to cover all structures coming within the scope of the claims appended hereto.

What we claim is:

1. In an apparatus for backing the backs of books, a pair of rounding and feed rollers between which a book is positioned, means for moving at least one of the rollers toward the other roller to cause the book to be engaged between the rollers, means for rotating the rollers in opposite directions to cause the book held between them to be rounded as the book is moved downwardly to position between the jaws and a backing roller, a backing roller located below the feed and rounding rollers and against which the book is brought upon its downward movement by the rounding and feed rollers, means for maintaining the backing roller in position to act as a stop to contact with the back of the book as the book is moved downwardly, means for swinging the backing roller through an arc across the back of the book while it is held in contact therewith, to thereby back said book, and means for controlling the point of contact of the rounding rollers with the book to thereby regulate the extent of movement of the book by said rollers in a direction toward the backing roller.

2. In an apparatus of the character described, a pivoted frame carrying a pair of rounding and feed rollers, means for rotating the rollers in opposite directions, means for raising and lowering the frame, a pair of jaws located below the frame, means for moving one jaw in a direction toward the other jaw to thereby cause a book to be engaged between and held by the jaws, a sliding supporting plate for positioning below the book to support the same, said plate being interposed between the rollers and the jaws and acting to support a book before the book is engaged between the rounding and feed rollers, a backing roller positioned below the jaws, means for swinging said roller through an arc while the same is positioned in contact with the back portion of a book that is held between the jaws and means for automatically varying the radius of the arc of movement of the backing roller according to the thickness of the book being backed.

3. In an apparatus for rounding and backing books, a slideable plate support for positioning below a book to be rounded and backed, rotatable means for engaging the opposite sides of the book and moving the same when the plate is removed from below the support, a backing roller against which the book is so moved by descending movement, jaws for engaging the lowered book, and means for swingably reciprocating the roller across the back of the book to back the same as the book is held by its jaws, said one of said jaws being moved toward and away from the other jaw.

4. In an apparatus for rounding and backing books, a slideable plate constituting a book support, said plate being located for positioning below a book and against which the back of the book is rested and which supports the book a pair of rounding and feed rollers above the support and between which a book is engaged, one of said rollers being moved toward and away from the other, a backing roller below the support toward and against which the book is moved by the rounding and feed rollers on withdrawal of the support, a pair of jaws below the support and between which the book is gripped and held with a rear portion extending beyond and below the jaws, at least one jaw being movable relatively to the other, means for reciprocating the backing roller through an

arc across the back of the book held by said jaws to thereby round the back of the book and means for varying the radius of the arc of movement of the backing roller according to the thickness of the book being backed.

5. In an apparatus for rounding and backing books, a pair of rotatable rounding and feed rollers between which a book is positioned, means for moving at least one of the rollers toward the other roller to cause the book to be engaged between the rollers, means for rotating the rollers in opposite directions to cause the book held between them to be moved downwardly, a backing roller located below the rounding and feed rollers and normally centrally positioned with respect to the descending book and against which the book is brought upon its downward movement by the rounding and feed rollers, means for holding the backing roller in contact with the back of the book, means for automatically positioning the backing roller at various distances from the jaws to contact with the backs of differently-sized books, and means for swinging the backing roller through an arc across the back of the book while it is held in contact therewith, to thereby back the rear of the said book.

6. In an apparatus of the character described, a pair of spaced elements for gripping a book to be rounded and backed, means for moving only one of the elements toward or away from the other to cause the book to be either gripped or released thereby, a backing roller positioned adjacent to the back of the book while the book is held between the gripping elements, means for causing the roller to be located centrally of the book when the book is held by the elements in a backing position to enable said roller to act as a stop against the book when the book is moved to backing position, means for then swinging the roller back and forth through an arc across the rear of the book to back the same, and means for automatically varying the radius of the arc through which the backing roller is moved.

7. In an apparatus as provided for in claim 6, wherein the spaced gripping elements are jaws, whereby the roller moving means is a linkage and includes hydraulic means.

effective on said linkage to reciprocate the roller while it is maintained in frictional contact with the back of the book.

8. In an apparatus as provided for in claim 6, wherein a chute is provided for receiving a rounded and backed book upon opening of the gripping means, and conveying means is located at the outlet end of the chute.
9. In an apparatus of the character described, a slideable supporting plate for location below a book for holding said book on edge with its back disposed downwardly and resting on and supported by the plate, a pivoted frame carrying a pair of rounding and feed rollers between which a book is positioned while held on the plate, means for rotating both rollers, means for moving one of the rollers toward and away from the second roller, means for retracting the supporting plate from below the rounding and feed rollers to thereby allow the book to be supported and moved downwardly by the rollers, a pair of jaws located below the rounding and feed rollers and between which the book is gripped and held with its back extending below said jaws, means for moving one of the jaws toward and away from the other jaw, a backing roller located below the rear of the book so held in contact therewith, means for adjustably positioning the backing roller to maintain the same in contact with the rear of the book so held, hydraulic means and co-operating linkage interposed between said hydraulic means and the backing roller for causing the backing roller to be moved through an arc across the back of the book while maintained in contact therewith to thereby back the same, and means for automatically changing the radius of the arc of movement of the backing roller according to the various thicknesses of books backed by the apparatus.
